UNITED STATES PATENT OFFICE.

AMOS G. FITZ, OF AUBURN, MAINE, ASSIGNOR TO FITZ DOUBLE PIVOT LAST COMPANY, OF AUBURN, MAINE, A CORPORATION OF MAINE.

LAST-SUPPORT.

No. 909,389.

Specification of Letters Patent.

Patented Jan. 12, 1909.

Application filed April 6, 1908. Serial No. 425,409.

To all whom it may concern:

Be it known that I, Amos G. Fitz, a citizen of the United States, residing at Auburn, in the county of Androscoggin and State of Maine, have invented new and useful Improvements in Last-Supports, of which the following is a specification.

My invention relates to improvements in lasts and more particularly to a construction of lasts designed to prevent splitting on horizontal lines of cleavage.

It is well known that lasts are subjected to great strain in certain processes of shoe making and that it frequently happens that the last splits horizontally at a point at or near the bottom of the thimble hole or about the vertical center of the last.

Lasts are sometimes made with a thimble and sometimes with a spindle whereby they are supported by a complementary member of the lasting or other machine. I have illustrated my invention in connection with lasts having both a thimble and a spindle support.

Figure 1 is an elevation partly in section of my invention as embodied in a last provided with a thimble and Fig. 2 is an elevation partly in section of my invention as embodied in a last provided with a spindle.

My invention consists in anchoring the last support, thimble or spindle, in the wood of the last below the medial line and in making the lower extremity of the support of less diameter than the upper part.

In Fig. 1 A represents a last and B a hollow last support provided with projections C which extend over and rest upon the solid wood of the last. Extending down through the bottom of the last support B is a rivet D headed on its upper end E in the last support and anchored against the bottom of the last by heading its lower end upon a bur F, said bur being drawn against the bottom of the last so as to compress the wood of the last around the rivet, thereby tending powerfully to resist any tendency of the last to split. I do not intend to limit myself, however, to forming the thimble and rivet of two separate parts.

In Fig. 2 the last support is in a spindle form provided with an overhanging flange G adapted to rest on the wood of the last at the top and with a bur H on the lower end adapted to be pressed against the bottom of the last with force sufficient to compress the

wood of the last, operating to resist a tendency of the last to split in the same manner as in the case of the thimble before described. The lower end I of the spindle may be of less diameter than the part that projects 60 above the last facilitating the use of the bur. Thus constructed the thimble or spindle has the power and force of a rivet headed against the last at both ends, thus holding the last under a positive strain or 65 tension at all times and tending to prevent horizontal fracture.

When the spindle is used in a last having a metallic heel plate, it is well to have it terminate a short distance above the plate, 70 the last being countersunk from the bottom as seen at J, the diameter of the bore of the countersink being greater than the diameter of the spindle so as to provide a bearing K for the bur. A plug L may be inserted in 75 the bore J to take the lasting tacks.

The advantages of my improved last are that a single device serves the purpose of a last support and also prevents the last from splitting horizontally under the strain 80 caused by the jack or other machine upon the last support. This is especially important in case of lasts in the smaller sizes.

Having thus described my invention and its use I claim:

1. The combination with a last having a last support-receiving hole therein, of a last support therefor provided with the means for anchoring it to the last below the vertical center and above the bottom thereof.

2. The combination with a last having a last support-receiving hole therein of varying diameters extending entirely through the last, of a last support therefor provided with means for anchoring it to the last at 95 either side of the vertical medial line of the last, the point of anchorage below said line being spaced apart above the bottom of the last.

3. The combination with a last having a last support-receiving hole therein extending entirely through the last, of a last support therefor provided with means for anchoring it to the last at either side of the vertical medial line of the last, the point of anchorage below said line being above the bottom of the last and the wood of the last adjacent, the anchoring means at one end being compressed.

4. The combination with a last having a 110

last support receiving hole therein extending entirely through the last, of a last support therefor comprising a hollow thimble and a solid extension, said extension being
5 anchored in the last above the bottom thereof.

In testimony whereof I have signed this

specification in presence of two subscribing witnesses this 24th day of March, 1908.

AMOS G. FITZ.
